CLAIM

The ornamental design for a muffler cover for motorcycles, as shown and described.

DESCRIPTION

FIG. 1 is a front elevational view of a muffler cover for motorcycles showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a front left perspective view thereof.

The claimed design is a muffler cover for motorcycles, the portions of which are dark-gray-colored in the drawings, and the light-grayed-out portions are illustrative purpose only and form no part of the claimed design.

The dark and light greyed surfaces do not represent a color nor a pattern but are intended to represent shading on the surface of the drawings.
